UNITED STATES PATENT OFFICE

JACKSON R. SCHONBERG, OF WESTFIELD, NEW JERSEY, ASSIGNOR TO STANDARD OIL DEVELOPMENT COMPANY, A CORPORATION OF DELAWARE

ART OF DISTILLATION UNDER VACUUM

Application filed June 12, 1928. Serial No. 284,867.

This invention relates generally to an improved method of vacuum distillation and more particularly to vacuum distillation at high vapor velocities for the manufacture of petroleum lubricating oils.

When a raw oil of dark color, such as reduced crude is subjected to continuous vacuum distillation by flashing the crude at high temperature into a tower, very often trouble is experienced caused by either one of two opposite effects: If the distillation is carried out at a high linear velocity of the vapors in the tower, parts of the crude are carried over by splashing and entrainment, impairing the color of the distillate. If, on the other hand, the distillation is carried out at a low vapor velocity, which, at a constant vacuum, is equivalent to a low feed rate, the crude remains too long in the heating coils and cracking sets in, injuring the viscosity, flash, and pour test of the oil.

The object of the present invention is to eliminate these two serious draw-backs of vacuum distillation for lubricating oils. In particular, a long series of experiments led me to the discovery, that, under carefully regulated conditions much higher vapor velocities can be maintained than have heretofore been considered to be practical.

The invention will be fully understood from the following description in connection with the accompanying drawings, in which

Fig. 1 is a diagrammatic side elevation of an illustrative form of the apparatus with some parts in section, and

Fig. 2 is an enlarged vertical section through the tower.

Referring to Fig. 1, the topped crude is charged preferably from the last still 1 of a continuous crude battery by pump 2 through pipe 3 into a heating conduit 4. The feed is heated in the latter to a high temperature, say 700° F., and is then discharged through line 5 into the tower 6 which serves both to disengage the vapors and to fractionally condense the distillate. The unvaporized heavy residue drops to the bottom of the tower, is drawn off through line 7 by pump 8 and is discharged through the cooler or heat exchanger 9 into the storage tank 10.

These bottoms may be worked up for asphalt or may serve as fuel oil.

The heavy lubricating oil condensed by cooling coils 11 and caused to flow into pan 12 by the deflector plate 13, flows by gravity through line 14 into the drum 15, from which it is discharged by pump 16 through lines 17, 19 and cooler or heat exchanger 18 into the heavy distillate tank 20. Cooling coils 11 may be of the usual pancake coil construction, through which the cooling liquid such as oil or water is circulated. The uncondensed vapors leave the top of the tower through line 21 and pass into condenser 22 where the light lubricating oils are condensed and flow by gravity into drum 23 from which they are removed by pump 24 through lines 25, 27 and cooler 26 into the light lubricating oil tank 28. Steam and permanent gases leave condenser 22 through line 29 and come into the barometric condenser 30 in which the steam is condensed. The permanent gases are removed through lines 31 and 32 by means of the vacuum pump 33. Lines 34 and 35 serve to directly connect drums 15 and 23 respectively to the vacuum pump.

Referring to Fig. 2, the hot feed coming from the heating conduit is discharged through line 5 tangentially into the annular baffle 36 provided with a cap 37 at the top and open at its lower periphery, which is preferably serrated. This baffle serves to separate the heavy, unvaporized residue from the vapors and to evenly distribute the latter. The vapors are forced to bubble through the liquid seal formed by the heavy residue at the bottom of the tower. The liquid level indicated by the dotted line 38 is held by the liquid level control 39. A manifold with steam sprays 40 serves for introduction of steam, if so desired, to strip light constituents from the bottoms.

The main feature of the process is the regulation of the vapor velocity. The actual velocity of the vapors in the tower can be computed knowing the gravity, the molecular weight, and the amount of the light and heavy distillate, the tower temperature below pan 12, and the vacuum held. In one

run, for instance, 3620 gallons of light and heavy distillate together were obtained per hour. The combined distillate had a gravity of 23° A.P.I., corresponding to 7.63 lbs./gal., and an average molecular weight of 290. The tower inlet temperature was 705° F. or 1165° Rankine. Inside cross section of the tower was 78.5 square feet. The absolute pressure was held at 0.97 inches of mercury. 5 Dry vacuum was used (without steam). There were obtained in the test run $\frac{3620}{3600} \cdot 7.63$ lbs. or $\frac{3620}{3600} \cdot \frac{7.63}{290}$ pound mols per second. Since the molal volume, 10 i. e., the volume of one pound mol (of gas or vapor) is 359 cubic feet under 1 atmosphere=29.92" of mercury pressure (p) at a temperature of 32° F.=492° Rankine. Since furthermore by the gas law 15 the volume of a gas (or vapor) is directly proportional to the absolute temperature and inversely proportional to the pressure, the volume of the distillate at 1165° Rankine under 0.97" of mercury pressure is 20

$$25 \quad \frac{3620}{3600} \cdot \frac{7.63}{290} \cdot 359 \cdot \frac{29.92}{0.97} \cdot \frac{1165}{492}$$

Dividing this volume by the inside cross section of the tower, 78.5", the linear vapor velocity is obtained as

$$30 \quad \frac{3620}{3600} \cdot \frac{7.63}{290} \cdot \frac{359}{0.97} \cdot \frac{29.92}{492} \cdot \frac{1165}{78.5} = 8.8 \text{ feet/second}$$

When steam is admitted through sprays 40, the volume of the vapors will be correspondingly increased. The velocity increase due to the amount of steam is calculated similarly 45 to the above example and is then added to the velocity due to the oil vapors alone.

The prior art employed comparatively low vapor velocities, such as 3-4 feet/second when distilling under high vacuum.

I discovered that, keeping the vacuum and the temperature at the various points of the apparatus constant, the feed rate can be increased until unusually high vapor velocities are obtained with the equipment described, 45 without thereby injuring the quality. Working, for instance, at an absolute pressure of 1 inch of mercury, vapor velocities exceeding 8 feet/second can be maintained, and the distillate goes off color due to liquid entrainment only when the vapor velocity reaches a value above 11 feet/second. I have also found that, as the vacuum increases the lower and upper limits of this optimum vapor 50 velocity increase in inverse proportion to the square root of the absolute pressure held in the tower. For instance at an absolute tower pressure of 0.5 inches of mercury the optimum vapor velocity ranges between

$$60 \quad \frac{8}{0.5\frac{1}{2}} \text{ and } \frac{11}{0.5\frac{1}{2}}$$

that is between 11.3 and 15.6 feet/second.

Among the principal advantages of such 65 vacuum distillation at high vapor velocity are the following—1) the maximum possible

feed rate is maintained, resulting in an increase of the capacity of the unit, 2) the possibility of cracking in the heating coils 4 is diminished since the time spent by the feed in said heating coils is decreased, 3) distillate of good color, flash and viscosity is obtained. 70

The apparatus in which the distillation is carried out may vary without departing from the scope of this invention. For instance 75 bell-cap plates can be placed in the tower. The vapor velocity is again calculated as above.

It will be understood that the invention is not limited to the particulars given but it is regarded as limited only in the following claims in which it is my intention to claim all inherent novelty as broadly as the prior art permits. 80

I claim:

1. In the high vacuum distillation of petroleum lubricating oils, the improvement which comprises vaporizing part at least of the oils under an absolute pressure of less than one inch of mercury, and passing the vapors through a fractionating zone at a linear velocity increased over approximately 8 feet per second in inverse proportion to the square root of the absolute pressure held in the tower while maintaining the vacuum. 90

2. In the vacuum distillation of petroleum lubricating oils, the improvement which comprises heating a stream of the oil to a temperature at which it tends to vaporize at 100 least in part, expanding the heated oil into an enlarged zone, passing the vapors evolved therein through a linear fractionating zone at a linear velocity between approximately

$\frac{8}{p\frac{1}{2}}$ feet per second and $\frac{11}{p\frac{1}{2}}$ feet per sec-

ond, and maintaining the absolute pressure in said fractionating zone at one inch of mercury or less equivalent to p inches of mercury or less. 110

3. In the vacuum distillation of petroleum lubricating oils the improvement which comprises passing the hydrocarbons through a heating zone of small cross section, then 115 through a fractionating zone in which separation of vapors from unvaporized hydrocarbons takes place, passing the vapors through said fractionating zone at a linear

velocity between approximately $\frac{8}{p\frac{1}{2}}$ feet per second and $\frac{11}{p\frac{1}{2}}$ feet per second, and main-

taining the absolute pressure in said fractionating zone at one inch of mercury or less equivalent to p inches of mercury or less. 125

JACKSON R. SCHÖNBERG. 130
